CLAIM

The ornamental design for a blade-type golf putter head, as shown and described.

DESCRIPTION

FIG. 1 is a top, rear, left side perspective view of a blade-type golf putter head showing my new design;

FIG. 2 is a bottom, front, right side perspective view thereof;

FIG. 3 is a top plan view thereof;

FIG. 4 is a front elevational view thereof;

FIG. 5 is a bottom plan view thereof;

FIG. 6 is a right side elevational view thereof;

FIG. 7 is a left side elevational view thereof; and,

FIG. 8 is a rear elevational view thereof.

The broken line drawing of a golf club shaft and handle is for illustrative purposes only and forms no part of the claimed design.
